(91.)

GEORGE A. KEENE.
No. 121,722.

Improvement in Clothes Driers.
Patented Dec. 12, 1871.

Fig. 1.

Fig. 2

Geo A. Keene INVENTOR

WITNESSES

Prosser, Miller, Parker
Henry, Neway.

UNITED STATES PATENT OFFICE.

GEORGE AUGUSTUS KEENE, OF LYNN, MASSACHUSETTS, ASSIGNOR TO HIMSELF AND MARTIN C. HEALD, OF SAME PLACE.

IMPROVEMENT IN CLOTHES-DRIERS.

Specification forming part of Letters Patent No. 121,722, dated December 12, 1871.

To all whom it may concern:

Be it known that I, GEORGE AUGUSTUS KEENE, of Lynn, in the county of Essex and State of Massachusetts, have invented a new and useful Improvement in Clothes-Driers, of which the following is a specification:

The nature of this invention consists in making a clothes-drier by arranging upon knotted strings a series of rods of suitable size to constitute, when suspended, a clothes-frame; and combining two or more such frames by means of spreaders suitably attached into a compact drier; in arranging, in connection with such composite drier, a suspending apparatus.

The drawing represents, in Figure 1, the said drier composed of three frames, when arranged to suspend from the ceiling or wall-brackets; and in Fig. 2, the same frame suspended from wall-sockets by aid of the spreaders.

The bars a a' a'' are bored at the ends and strung upon cords b , knotted to prevent the sliding of the bars, or clamped or fastened to them in any suitable manner. To prevent the contact of the frames thus formed spreaders d d' are also attached to the cords, preferably so as to be readily detached, by scarfs f and g from all but one of the cords b . The upper spreader d is made so as to fit into wall-sockets h , so that the drier may either be hung from a ring, K , or suspended by the spreader d , as preferred.

The compactness, space for drying, and lightness of this contrivance render it an important improvement in laundry furniture.

I claim—

1. The arrangement of the clothes-frames a a' a'' , hung upon cords b , and having spreaders d' and d , of which d is longer than d' , in combination with a suitable suspending attachment, substantially as described.
2. The arrangement of the drier, consisting of the clothes-frames a a' a'' strung upon cords b and having spreaders d d' , with wall-sockets h , substantially as and for the purpose described.

GEO. A. KEENE.

Witnesses:

THOS. WM. CLARKE,
JOHN HALEY.

(91)